UNITED STATES PATENT OFFICE.

JAMES S. DAYTON, OF CUMBERLAND, MARYLAND.

RAIL-Straightening Press.

Application filed December 13, 1920. Serial No. 430,298.

To all whom it may concern:

Be it known that I, JAMES S. DAYTON, citizen of the United States, residing at Cumberland, in the county of Allegany and State 5 of Maryland, have invented new and useful Improvements in a Rail-Straightening Press, of which the following is a specification.

This invention relates to a rail straightening press, and the object is to straighten steel 10 rails as they are passed between the rolls of a series, mounted as herein indicated, in order that any portion of a rail which is warped or deflected from proper alinement, may be placed under that degree of pressure 15 required to restore it to correct position.

A further object is to provide means for effecting the above mentioned result and applying the correct degree of pressure by means automatically controlled, so that the 20 resistance offered by the rail to the pressure members may determine the pressure to be applied in correcting the error.

A still further object is to provide a straightening element or elements including 25 a pressure device under pneumatic control, the degree of pressure to be applied in straightening a rail being determined by the pressure exerted on a body of oil within a cylinder the plunger of which is acted upon 30 by the rail or the deflected portion thereof, an additional plunger being under pneumatic control and forced into engagement with the work under pressure determined in the manner indicated.

A still further object is to provide a maximum air pressure to be reduced automatically to a degree determined by the pressure on the body of oil.

A still further object is to provide controlling valve mechanism comprising a primary valve and valve chest, an intermediate valve and valve chest, and an upper valve 40 and casing therefor, the pressure on the body of oil within the cylinder before mentioned being manifested in the primary valve chest and operating the valve therein for admitting air to the intermediate valve chest and operating the valve therein, the valve last named admitting air pressure to the upper 45 chest from which it is discharged to the pneumatic cylinder controlling the pressure element directly contacting with the rail to be straightened.

A still further object is to provide in connection with the upper or third valve chest

a blowoff valve automatically controlled, so that the pressure is reduced from a maximum of say—two hundred pounds—to the pressure required to correct a given error in a rail to be straightened. 60

A still further object is to provide an equalizing device for the primary valve.

A still further object is to provide a so-called slip valve for restoring the intermediate valve, by air pressure, to normal position. 65

A still further object is to provide means for maintaining the pressure in the upper or third valve chest, after the required pressure has been determined, and simultaneously cutting off an oil connection from the chamber of the intermediate valve with the corresponding chamber of the intermediate valve of another pressure element. 70

A still further object is to provide a plurality of pairs of rolls between which the rail to be straightened is fed, a plurality of pressure elements positioned to engage said rail from opposite directions, and means automatically controlled for applying pressure 75 to the rail in opposite directions, by pneumatic devices automatically controlled in the manner indicated.

In the drawings:

Figure 1 is a top plan view of the press. 85

Figure 2 is an end elevation, illustrating the means for imparting movement to the rolls from the motor shaft.

Figure 3 is a section on line 3—3 of Figure 1. 90

Figure 4 is a view partly in vertical section, with portions in elevation as they would appear looking from the right in Figure 1.

Figure 5 is a view in elevation and section, showing the valve mechanism above the 95 pneumatic cylinder on the left and the oil cylinder at the right.

Figure 6 is a view showing a portion of the valve mechanism in top plan and showing the upper valve chest in longitudinal section. 100

Figure 7 is a view showing the intermediate valve chest and primary valve chest in longitudinal section, and also showing in section the casing of the valve by which the pressure is reduced from the maximum, to that degree required to effect the correction of a given error in a rail. 105

Figure 8 shows the oil cylinder in end elevation and above that cylinder the valve 110

mechanism, the primary valve being in longitudinal section.

Figure 9 is a vertical section through the upper valve and the intermediate valve chest, the intermediate valve being in starting position, and the oil cylinder being shown in elevation.

Figure 10 is a horizontal section through the intermediate valve chest and the primary valve chest, the intermediate valve having moved to operative position.

Figure 11 is a vertical section through the upper valve chest and the intermediate valve chest, both of the valves having moved to operative position.

Figure 12 is a detail in section on line 12-12 of Figure 6.

Figure 13 is a detail in longitudinal section through the slip valve, operating on the stem of the intermediate valve for admitting air to return the intermediate valve to normal position.

The rails to be straightened are passed between rollers arranged in pairs, as shown particularly in Figures 1 and 2. One roll of each pair is stationary, being designated 10, and having its circumference provided with a broad flat groove for engaging the flange of the rail. The opposing roll 12 is provided with a groove 13 for engaging the head of the rail, and the roll 12 is movable toward the work under air pressure applied through the mounting means. This roll is mounted in a cross head 14 operating in guides 15 and being controlled by a plunger 16 operating in a pneumatic cylinder 17, the air feed to this cylinder being under the direct control of an operator. Two sets or pairs of rolls 10 and 12 are shown in Figure 1, and movement is imparted to the rolls through the gearing shown in Figure 4 and elsewhere. A worm shaft 20 carries a bevel gear wheel 21 meshing with a gear wheel 22 on a shaft 23 carrying a gear wheel 24. This wheel 24 meshes with a pinion 25 on the shaft 26 of a motor 27 shown in Figure 1.

Meshing with the worm shaft 20 are worm wheels 28, 29, 30 and 31 keyed to vertical shafts 33, 34, 35 and 36, the lower ends of these shafts being mounted in thrust bearings. The movable rolls 12 are mounted on stub shafts 35' connected by a shaft member 36', having universal movement with the vertical shaft in alinement or approximate alinement with the axis of the roll to be driven. The rolls 10 are rotated through shaft sections 38 and 39 connected with the vertical shaft in alinement with the axes of these rolls. The rolls 41 and 42 of the presses are similarly driven from vertical shafts 42 and 43 each carrying a worm wheel 44 or 45 as the case may be and having connection with a shaft section 45^a, permitting universal movement, in the manner shown in Figure 3. The rolls of the presses

operate or rotate in cross heads 44' and 45' movable in guides 46 and each having connection with a plunger 48 operating in a pneumatic cylinder 50, this plunger operating under air pressure automatically controlled in the manner to be described below.

The piston rod 49 also carries a plunger 51 movable in an oil cylinder 52, and the pressure exerted on the body of oil is proportional to the pressure produced on the press roll 41 when the slightly bent or deflected portion of a rail engages the roll last named. This pressure on the body of oil is manifested in one of the chambers of the valve mechanism and serves to determine the degree of air pressure applied to the pneumatically controlled plunger for correcting the error in the rail and straightening the latter.

Assuming that a rail has been engaged by the rolls, 10 and 12, the operator having permitted air to enter cylinder 17, for the purpose of throwing the roll 12 to operative position, and assuming that a deflected or slightly bent portion of the rail has engaged a roll 41 of one of the presses, pressure will be transmitted through piston rod 49 and plunger 51 to the oil within cylinder 52. This cylinder has connection by means of a duct 54, under the control of a valve 55 with the oil chamber 60 of the primary valve chest 61. The oil exerts pressure on valve 62 and moves the valve toward the right in Fig. 10 and elsewhere, causing the valve element 63 on valve stem 64 to open a port 65, permitting air to pass from the intake 66 through the valve chest and thence into air duct 67 leading to the space at the left of the intermediate valve chest 68, with the result that the intermediate valve 70 is moved to a position for permitting air to pass to the upper or third valve chest designated 71. Air entering at the left of upper valve 72 throws that valve to the right, and permits air to pass from inlet 73 to the outlet 74 of this upper valve chest, exhaust port 71' having been closed by valve 72, the air passing thence through air duct 75, casing 76, port 77 to the pneumatic cylinder of the press. The air passing through the duct last named is under two hundred pounds pressure, the pressure being reduced automatically to the pressure required at a given time, by means of the valve 80. This valve controls the port 81 and a spring 82 tends to hold the valve to seat.

The stem 82' of valve 80 carries a plunger 83 operating in a chamber or cylinder 84 which has communication with an air inlet 85. This inlet is under the control of a valve 87, automatically controlled, as indicated, below, and the inlet mentioned is in communication with air duct 67, as indicated in Figure 12. The valve 80 may be adjusted by varying the tension of the

spring, adjusting sleeve 88 and nuts 89, permitting of the operation. Assuming that the valve 80 is set to open at a pressure below the initial pressure of 200 pounds but sufficient to overcome the resistance offered by the warped rail, it will be apparent that the pressure in the casing 76 will be reduced accordingly before the air enters the pneumatic cylinder.

10 One of the especially important features of the invention is the control of the valve 80, and this is effected automatically, since the valve is set in the manner indicated but is further subject to the air pressure 15 below the plunger 83 on the stem of the valve 80. This pressure is in turn determined by the pressure in the primary valve chest, in view of the connection between the air duct 67 and the primary valve chest, 20 the extent to which the port 65 is opened depending upon the oil pressure at the left hand or inlet end of this valve chest. As previously explained, the oil pressure is proportional to the pressure exerted on the 25 movable elements of the press, incident to the bent or deflected portion of a rail.

It will be observed, therefore, that the degree of air pressure required for straightening a given portion of the rail, is determined automatically by the initial pressure exerted on the movable element of the press as the result of the distortion of the rail. The spring of the regulating valve 80 is under a minimum compression corresponding to a pressure in the pneumatic cylinder equalling or slightly exceeding the elastic limit of the rail. This minimum compression is controlled by nuts 89. An adjusting sleeve 88 limits the maximum pressure, being engaged by a fixed collar 88' on the valve stem. The valve or cock 87 is closed at the proper time as indicated below, in order to prevent the relief of pressure in the oil cylinder 52, during the working stroke, from altering or affecting the pressure controlling valve 80. The control of the valve 87 is effected through the operation of the upper valve, and will again be referred to.

50 Another important feature of the invention is the equalizing springs 90 of the primary valve 62, the function of which is to permit of the opening of the port 65 to such an extent that the pressure on the intermediate valve will be proportional to the oil pressure in the valve chest 61.

The right hand end of the intermediate valve chest 68 is connected by a pipe 91, under the control of a valve 92, with the other press, the valve 92 being controlled by the upper valve 72. When the upper valve moves to operative position, that is to the right, the valve 92 is closed, so that there will be no interference, by the other press, with the operation of the intermediate valve

of the press under consideration. A spring held trip 94 on the stem 95 of the upper valve throws the arm 96 of the valve 92, for the purpose indicated. A spring held trip 97 on the other end of this valve stem cooperates with an arm 98 on the stem of the valve 87, for a like purpose. 70

Referring further to the operation of the intermediate valve, and to Figures 7 and 10, air inlet ports are shown at 101 and 102 and an exhaust port 103 is located as shown. Ports 104 and 105 permit air to pass to the upper cylinder or valve chest 71. The stem of the intermediate valve carries four valve elements 70' and the oil piston 106 is acted upon by the pressure of oil from the other press when the valve 92 is open. In order to return the intermediate valve to normal position after operation, we provide a slip valve 110 comprising three disks 111 formed on a body 112 slidable on the valve stem. These disks are provided with apertures 113 for the purpose indicated below. At the proper time air passing from the duct 115, passes between the disks and through the apertures therein, against the oil piston 106, the end disk 116 on the valve stem being also apertured.

Air passing from the intermediate cylinder or valve chest 68 enters the upper valve chest through port 120 and throws upper valve 72 to the right, placing the ports 73 and 74 in communication, whereby air is permitted to pass through duct 75, casing 76, and thus to the pneumatic cylinder. 100

The press having operated under the air pressure in the pneumatic cylinder, exceeding the elastic limit of the rail, the pressure in the oil cylinder 52 is relieved, and the primary valve returned to normal position under the action of the spring 90. The left end of the intermediate valve chest is open to the exhaust through port 65, and air passes from intake 121 through the primary valve chest, duct 115 and the apertured disks of the slip valve 110, to the right end of the intermediate valve chest, returning the intermediate valve 70 to normal position, and incidentally returning the slip valve 110. Air is then admitted to the right end of the upper valve chest 71, port 124 having been held slightly open by spring 125. The left end of the upper valve chest is open to exhaust port 126, and the upper valve 72 returns to normal position under air pressure, cutting off the air to pneumatic cylinder 52 and opening valves 87 and 92 associated with the regulating valve 80 and the oil line to the intermediate valve chest of the other press. In opening these valves the collars 129 engage the arms controlling the valves. The machine is then ready for further automatic operation in straightening another bend in the rail. Exhaust ports 61' and 62' of cylinder 61 and exhaust ports 103

and 131 of the intermediate valve chest serve an obvious purpose, and where desirable coil springs are located as shown to prevent the sticking of the valves. In the event of over travel of the plunger in the pneumatic cylinder, through accident, pressure in the cylinder is relieved through the port 130.

The rail being operated upon travels through a guard member 135, of channel formation, shown especially in Figures 1 and 3. Housing or boxing elements 136 appear in these views and elsewhere, and frame elements of rectangular cross section are shown at 138. Springs 139, 140 return the plungers of the movable rolls to normal position. Elements 141 serve to take up wear in the guideways of the cross-heads.

What is claimed is:

1. In a machine of the class described, power operated means for applying pressure to the work, and means controlled by the initial pressure of the work on an element of the means first named, and by the movement of said means, for controlling the degree of pressure to be applied through the power operated means.

2. In a machine of the class described, a pressure roll, power operated means for applying pressure through said roll, and means controlled by the initial pressure exerted on the roll by the work, and by a retracted movement of said power operated pressure roll, for governing the operation of the power operated means.

3. In a machine of the class described, a rail straightening pressure element, a fluid pressure device for imparting movement to the pressure element, and means controlled by the initial pressure exerted on the pressure element by the work, and by movement of said rail straightening element, for controlling the degree of pressure to be applied to the element first named.

4. In a machine of the class described, a rail straightening pressure element, a fluid pressure device for imparting movement to the pressure element, and a fluid pressure device for determining by movement of said rail straightening element the degree of pressure to be applied through the fluid pressure device first named.

5. In a machine of the class described, a rail straightening pressure element, a fluid pressure device for imparting movement to the pressure element, and means controlled by movement of the rail straightening element for automatically determining the degree of pressure to be imparted through the fluid pressure device, and including mechanism controlled by liquid pressure.

6. In a machine of the class described, a rail straightening pressure element, a fluid pressure device for imparting movement to the pressure element, and means controlled by movement of the rail straightening ele-

ment for determining by mechanical pressure and fluid pressure the degree of pressure to be applied to the element first named.

7. In a machine of the class described, a pressure element, a pneumatically operated plunger, means controlled therethrough for exerting pressure on a body of liquid, and means responsive to pressure on the liquid for controlling the degree of air pressure to be applied to the plunger. 70

8. In a machine of the class described, a pressure element, a pneumatically operated plunger, means controlled therethrough for exerting pressure on a body of liquid, and air operated means responsive to pressure on the liquid for controlling the degree of air pressure to be applied to the plunger. 75

9. In a machine of the class described, a pressure element, a pneumatically operated plunger, means controlled therethrough for exerting pressure on a body of liquid, means responsive to pressure on the liquid for controlling the degree of air pressure to be applied to the plunger, said means last named including a plurality of reciprocable valves. 80

10. In a machine of the class described, a pressure element, a pneumatically operated plunger, means controlled therethrough for exerting pressure on a body of liquid, means responsive to pressure on the liquid for controlling the degree of air pressure to be applied to the plunger, said means last named including a plurality of slideable valves and a spring controlled regulating valve. 95

11. In a machine of the class described, a pressure element, a pneumatically operated plunger, means controlled therethrough for exerting pressure on a body of liquid, air operated means responsive to pressure on the liquid for controlling the degree of air pressure to be applied to the plunger, said means last named including a valve for reducing the maximum air pressure to a predetermined degree. 100

12. In a machine of the class described, a pressure element, a pneumatically operated plunger, means controlled therethrough for exerting pressure on a body of liquid, air operated means responsive to pressure on the liquid for controlling the degree of air pressure to be applied to the plunger, said means last named including a spring controlled and air controlled valve for reducing the maximum air pressure to a degree determined automatically by the character of the work. 115

13. In a machine of the class described, power operated pressure elements and governing means therefor including a spring controlled and air controlled valve for reducing the maximum air pressure to a degree determined automatically by the character of the work. 120

14. In a machine of the class described, an element for applying pressure to the 130

- work, and governing means therefor including a primary valve actuated by fluid pressure, a second valve operated under fluid pressure and controlled by the valve first named, and a third valve controlled by the second valve and acting to control the movement of the element applying pressure to the work.
15. In a machine of the class described, an element for applying pressure to the work, governing means therefor including a primary valve actuated by fluid pressure, a second valve operated under fluid pressure and controlled by the valve first named, a third valve controlled by the second valve and acting to control the movement of the element applying pressure to the work, and a regulating valve for reducing a maximum air pressure to the extent required for the character of the work.
16. In a machine of the class described, an element for applying pressure to the work, governing means therefor including a primary valve actuated by fluid pressure, a second valve operated under fluid pressure and controlled by the valve first named, a third valve controlled by the second valve and acting to control the movement of the element applying pressure to the work, and a spring controlled and air controlled regulating valve for reducing a maximum air pressure to the extent required for the character of the work.
17. In a machine of the class described, an element for applying pressure to the work, and governing means therefor including a mechanically controlled and air controlled valve for reducing a maximum air pressure to the extent required for the character of the work, and means for retaining the reduced pressure constant during the operation of the element first named.
18. In a machine of the class described, a plurality of elements for applying pressure to the work from opposite directions, and governing means for each element including a valve for reducing a maximum air pressure to the extent required for the character of the work engaged by one of the elements first named, and means for rendering the governing means associated with one of said elements applying pressure to the work, inoperative, while the other of said elements is operating.
- 55 19. In a machine of the class described, a pressure element, a second pressure element movable in a direction opposite to that first named, means automatically operated for governing the operation of each pressure element and preventing said elements from acting simultaneously, said means including plungers and devices permitting, and at times preventing, the flow of fluid between the plungers.
- 60 20. The combination with a press, of a second press movable in a direction opposite to that first named, and means automatically operated for governing the operation of each press and preventing the presses from acting simultaneously, said means last named including a cylinder associated with each press and adapted to receive a body of oil, an oil plunger for each cylinder, and means for placing said cylinders in communication.
- 75 21. In a machine of the class described, an element for applying pressure to the work, and governing means therefor including a primary valve and an equalizing spring therefor, said valve being actuated by air pressure, a second valve operated by air pressure and controlled by the valve first named, and a third valve controlled by the second valve and acting to control the movement of the element applying pressure to the work.
- 80 22. In a machine of the class described, an element for applying pressure to the work, and governing means set in operation by the movement of the element applying pressure and including a primary valve actuated by fluid pressure, an equalizing spring for said valve, and devices directly controlled by said valve for governing the movement of the element applying pressure to the work.
- 85 23. In a machine of the class described, an element for applying pressure to the work, and governing means set in operation by the movement of the element applying pressure and including an adjustable spring held valve and pneumatic and automatic means controlling said valve and determining the pressure acting upon the element first named.
- 90 24. In a machine of the class described, an element for applying pressure to the work, and governing means therefor including a primary valve actuated by fluid pressure, a second valve controlled by the valve first named, means for automatically returning the second valve to normal position, a third valve controlled by the second valve, and means controlled by said third valve for determining the pressure admitted to the element first named.
- 95 25. In a machine of the class described, an element for applying pressure to the work and governing means therefor including a primary valve, a second valve controlled by the valve first named, a stem for the second valve, a slide valve member on the stem and admitting air pressure for returning the second valve to normal position, and a third valve controlled by the second named valve and directly determining the pressure under which the element first named is operated.
- 100 26. In a machine of the class described, an element for applying pressure to the work.

- work, and governing means therefor including a primary valve actuated by fluid pressure, a second valve operated under fluid pressure and controlled by the valve first 5 named, a third valve controlled by the second valve and acting to control the movement of the element applying pressure to the work, and means for automatically returning all of said valves to normal position.
27. In a machine of the class described, a plunger operating under air pressure, and valve mechanism for controlling the pressure of air on the plunger and including a 15 fluid operated valve, a stem therefor, and a second valve member slidable on the stem and having apertures therethrough, means for admitting air through the second valve member for returning the valve first-named 20 to normal position, and means controlled by the valve first named for determining the pressure applied to the plunger.
28. In a machine of the class described, a plunger operating under air pressure, and 25 valve mechanism for controlling the pressure upon the plunger and including a fluid operated valve, an equalizing spring therefor, a second valve, an auxiliary valve for returning the second valve to normal position 30 under air pressure, an additional valve controlled by the second named valve, and a regulating valve for reducing a maximum air pressure to a predetermined degree.
29. In a machine of the class described, 35 a plunger operating under air pressure, valve mechanism for controlling the pressure upon the plunger, and including a fluid operated valve, an equalizing spring therefor, a second valve, an auxiliary valve for returning 40 the second valve to normal position under air pressure, an additional valve controlled by the second-named valve, a regulating valve for reducing a maximum air pressure to a predetermined degree, said regulating 45 valve acting under the influence of a resilient device and under air pressure determined by the valve first named.
30. In a machine of the class described, a plunger operating under air pressure, 50 valve mechanism for controlling the pressure upon the plunger and including a fluid operated valve, an equalizing spring therefor, a second valve, an auxiliary valve for returning the second valve to normal position 55 under air pressure, an additional valve controlled by the second-named valve, a regulating valve for reducing a maximum air pressure to a predetermined degree, and means controlled by said additional valve 60 for rendering the regulating valve inopera-

tive after the beginning of the working stroke of the plunger.

31. A rail straightening press, comprising pressure elements for engaging a rail from opposite directions, and automatically controlled fluid pressure mechanism causing one of said elements to act to the exclusion of the other said automatic control including ducts and valves governing the flow of fluid between portions of the fluid pressure mechanism.

32. A rail straightening press, comprising a plurality of pairs of rolls, the rolls of each pair engaging a rail from opposite directions, a plurality of pressure elements for engaging the rail between said pairs of rolls, and automatically controlled fluid pressure mechanism causing one of said pressure elements to act to the exclusion of the other said automatic control including ducts and valves governing the flow of fluid between portions of the fluid pressure mechanism.

33. In a device of the class described, a plurality of pairs of rolls, the rolls of each pair engaging the rail from opposite sides, and one roll of each pair being movable bodily toward the other, pneumatic means for effecting said movement, and pressure rolls for engaging the rail from opposite directions and between said pairs of rolls.

34. In a device of the class described, a plurality of pairs of rolls, the rolls of each pair engaging a rail from opposite sides and one roll of each pair being movable bodily toward the other, pneumatic means for effecting said movement, and automatically controlled pressure rolls for engaging the rail from opposite sides, between said pairs of rolls.

35. In a device of the class described, a plurality of pairs of rolls, the rolls of each pair engaging a rail on opposite sides and one roll of each pair being movable bodily toward the other, a worm gearing for imparting movement to the rolls, pneumatic means for effecting the movement of one roll of each pair toward the other, and pressure rolls for engaging the rail on opposite sides between said pairs of rolls.

36. In a device of the class described, a worm shaft, driving means for the shaft, a plurality of pairs of rolls, a shaft for driving the rolls, gearing for imparting movement to the shaft last named from the worm shaft, one roll of each pair being bodily movable toward the other, and a flexible connection permitting such movement with reference to the shaft driving the rolls.

In testimony whereof I affix my signature.
JAMES S. DAYTON.
